Specification for Design.

Patented Dec. 11, 1917.

Application filed October 2, 1917. Serial No. 194,403. Term of patent 14 years.

To all whom it may concern:

Be it known that I, JULES HAUVENTTE-MICHELIN, a citizen of the French Republic, residing at New Brunswick, in the county of Middlesex and State of New Jersey, have invented a new, original, and ornamental Design for Tire-Treads, of which the following is a specification, reference being had to the accompanying drawings, forming a part thereof, in which—

Figure 1 is a plan view showing the design of the tire tread; and

Copies of this patent may be obtained for five cents each, by addressing the "Commissioner of Patents
Washington, D. C."

Fig. 2 shows a section along the broken line 2—2 and represents the elevated portions of the tire tread constructed according to my new design.

I claim as my invention:

The ornamental design for a tire tread as shown.

In testimony whereof I affix my signature.

JULES HAUVENTTE-MICHELIN.
